(57) **CLAIM**

The ornamental design for a mixing bowl with friction material, as shown and described.

DESCRIPTION

FIG. 1 is a top plan view of a mixing bowl with friction material showing our new design;

FIG. 2 is a front elevational view thereof;

FIG. 3 is a rear elevational view thereof;

FIG. 4 is a right side elevational view of the mixing bowl with the friction material; the left side elevational view is a mirror image thereof;

FIG. 5 is a bottom plan view thereof; and,

FIG. 6 is a perspective view thereof.
